ABSTRACT OF THE DISCLOSURE

An apparatus for the stack-form deposition of sections of a tape in the form of individual shapes or sections pre-formed by folding of such tape having a receptacle within which the stack can be formed and a method for withdrawing the air away from the stack parallel to the pre-folded edges so as to prevent the formation of an air cushion beneath each newly impacting tape section.

In high speed printing apparatuses, as for example, tabulating machines which are used as output units of electronic computing devices, it is to be observed, as a rule, that there forms first under the sections of the pre-folded paper strip or web striking the stack, an air cushion which easily leads to difficulties, especially to the rolling in of an edge of such section. Even in laterally open receiving receptacles frequently the air cushion cannot escape rapidly enough, especially with respect to the use of types of paper with low specific gravity, particularly single-layer papers. The invention, therefore, is directed to a solution for this.

The device according to the invention for the stack-forming deposition of strips, in the form of individual sheets or sections resulting through prefolding of a band is characterized by suction means arranged adjacent the deposition area, by which the formation of an air cushion under each newly entering sheet or strip section as it strikes the stack being formed, is prevented.

The invention is hereinafter explained in detail with the aid of the drawings illustrating an example of construction; in which:

FIG. 1 is a schematic figure illustrating the phenomenon which, as a rule, is observed in the conventional depositing devices;

FIG. 2 is a similar view illustrating a paper depositing in the desired form, such as is achieved by the invention; and

FIGS. 3 and 4 represent a front and a side view, respectively, of a receiving or deposition device according to the invention.

As initially stated, in conventional depositing devices, especially those involving use of light manifold paper and the like, in the manner shown in FIG. 1, an air cushion forms under the sheet or strip section which is the last to strike the stack, which air cushion only slowly escapes. Here there can easily occur a rolling in of an edge of such sheet or section. With the invention, however, it is possible to dissipate such an air cushion very rapidly, or even to prevent its arising, so that the individual sections are faultlessly deposited in the manner illustrated in FIG. 2.

In FIGS. 3 and 4 there is represented a carriage or base 1, such as is used for paper supply at the feed side, as well as at the receptacle for a paper stack at the discharge side of a rapid printer or the like. On the carriage 1 there are arranged guide means illustrated as being in the form of rods 2, which define oppositely facing opened side walls, operative to guide the individual sections,

2

formed by prefolding, of the paper web or strip 3, whereby it will settle in a predetermined manner, i.e., in the form of a stack 4. Adjacent the lateral side of stack 4, at a short distance therefrom, is disposed a suction means or unit 5, by means of which, according to the invention, the air cushion, otherwise forming according to FIG. 1, is rapidly drawn off by suction.

The suction unit 5 consists, for example, of a single exhaust fan. In order to arrive at a more uniform effect on as great as possible a portion of the face surface of stack 4, it may be desirable, under some circumstances, to arrange several such fans alongside and/or over one another. For this purpose there are especially well suited the very flat radial blade fans available on the market, making use of induction motors, for example, external rotor induction motors. Such a form of construction is particularly desirable when there is only a small space available for the suction device.

However, a still more uniform effect can be achieved with suction units 5 if space requirements permit in the manner illustrated in FIGS. 3 and 4, in which a blower 6 is mounted, together with a funnel-shaped duct 7 disposed in front of it, on a support stand. In a simple form the block 8 is merely placed on the carriage 2, in which case it is expediently equipped with rubber feet as sliding protection.

In the example illustrated, however, the stand 8 is secured to the carriage 1 by bolting. If paper strips of differing width are to be used, a simple possibility of adjustment for the stand 8 consists, for example, in the provision of wing nuts 9, and cooperable screw bolts are provided, which extend through corresponding elongated holes in the base plate 10 of the stand 8 to provide an adjustment means for the suction means 5. A still greater possibility of adjustment results if there are provided in the base plate of the carriage 1 the familiar T-shaped grooves, in which correspondingly formed screw bolts are so carried that in the loosened state thereof they can be slid along in the grooves. Grooves, like elongated holes, extend in the representation of FIG. 3, parallel to the drawing plane.

Another possibility consists in mounting the suction device on the machine itself, as for example, supporting it on rails.

For the achievement of a more uniform suction effect, especially in the case of a very shallow funnel-shaped duct member 7, such as will be used, as a rule, for reasons of available space, it is recommended that the latter be covered on the side facing the stack 4 by an air distributive screen, for example in the form of a perforated plate 11. Such a screen may additionally serve as a guide for the paper strip 3, in order to prevent the possibility that parts of the same will be drawn into the blower 6.

Through suitable choice of the perforation size and/or of the perforation spacings on plate 11 it is further possible to achieve air speeds as may be desired, and thereby create the desired suction effect over the cross section of the member 7. If, as is sometimes the case, a powerful vacuum source is available, the suction means then can simply consist of an inflow duct connected to the suction line thereof, in particular in a similar form to the member 7 of the suction unit 5 according to FIGS. 3 and 4. Under some circumstances even the suction apparatus of a vacuum cleaner can be used as the suction blower.

As has been proved, starting from a certain width of the paper strip 3, dependent, among other things, on the specific weight of the paper, a suction device corresponding to that of FIG. 3 mounted at one side no longer individually suffices, even if its output could be made correspondingly great. Then warping of the paper strip can occur, which in turn may interfere with the desired de-

positing. In such a case the mounting of such units or suction means 5 and 5', according to the invention, on two sides will promote the desired result.

On the other hand, improvements in the suction effect can under some circumstances also be achieved if there is arranged at a short distance from the side of stack 4 remote from the suction unit a solid wall in the position where a screen or perforated plate 11' of the suction device 5' is illustrated in FIG. 3, which tends to effect a partial restriction or sealing of the volume of air being drawn off with respect to outside air.

Obviously the device according to the invention can undergo various modifications corresponding to the most diverse requirements and structural forms of, for example, printing devices, without departing from the concept of the invention. In particular, it is possible, as previously mentioned, for the suction system according to the invention to also be used to advantage in depositing devices for sheet-like foils.

Changes may be made within the scope and spirit of the appended claims which define what is believed to be new and desired to have protected by Letters Patent.

We claim:

1. An apparatus for receiving a strip from a discharge side of a strip handling device and for depositing of the strip into a stack, the strip having a form of individual sheets or sections pre-formed by folding of the strip, said apparatus comprising:

a receptacle having a base and oppositely facing guide means for guiding and positioning the strip as it forms the stack upon the base, said guide means being at-

5
10

tached to said base and defining oppositely facing sides with openings therein of said receptacle; and suction means disposed adjacent said receptacle at a lateral side extending between said guide means so that the air is withdrawn from between the sheets or sections parallel to the prefolded edges of the strip to assist in forming the stack in said receptacle.

2. An apparatus according to claim 1, wherein said receptacle includes a wall attached to said base opposite to said suction means and extending laterally between said opened sides to partially restrict the flow of air through the stack at the end opposite said suction means.

3. An apparatus according to claim 1, in which said apparatus includes a second suction means attached to said base opposite to said first mentioned suction means so that the air is withdrawn from between the sheets or sections of the strip at both ends to assist in forming the stack.
